[57] ABSTRACT

Diphenylamines of the formula

wherein R₁ and R₂ each independently represent hydrogen, halogen or lower alkyl containing one to four carbon atoms with at least one of R₁ and R₂ being other than hydrogen; R₃, R₄, R₅, R₆, and R₇ each independently represent hydrogen, methoxy, or lower alkyl optionally substituted with hydroxy, carbamyl, piperidinyl or acylamino; R₃ and R₆ or R₄ and R₇ also optionally forming together with the carbon and nitrogen atoms to which they are attached, a dihydrooxazine or pyrrolidine heterocycle; and Z represents amino, acylamino or hydroxy; and the acid salts of said diphenylamines. These diphenylamines are usefully employed in cosmetic compositions for the hair including hair dye compositions and hair setting lotion compositions.

DIPHENYLAMINES FOR DYEING KERATINOUS FIBERS

This application is a continuation-in-part of our application Ser. No. 61,833, filed Aug. 6, 1970.

This invention relates to novel leuco derivatives of indoanilines, a process for preparing the same and to novel cosmetic compositions containing these leuco derivatives for dyeing keratinic fibers such as human hair. The leuco derivatives of indoanilines of this invention are colorless compounds which when applied in an aqueous solution to the fibers to be dyed, oxidize in the air or in the presence of another oxidizing agent thereby giving the corresponding indoanilines, which on the other hand are colored compounds directly responsible for dyeing of the fiber. The dyes thus obtained present qualities of fastness and intensity of dyeing superior to those dyeings obtained by direct application of indoanilines, because of the better solubility of the leucoderivatives of these compounds.

More specifically, the present invention relates to a compound of the formula:

wherein R₁ and R₂ each independently represent a member selected from the group consisting of hydrogen, halogen, and lower alkyl containing one to four carbon atoms, with the proviso that at least one of R₁ and R₂ is other than hydrogen; R₃, R₄ and R₅ each independently are selected from the group consisting of hydrogen, methoxy, lower alkyl containing one to four carbon atoms and lower alkyl containing one to four carbon atoms and lower alkyl containing one to four carbon atoms and substituted with a member selected from the group consisting of hydroxy, carbamyl, piperidinyl and acylamino; R₆ is selected from the group consisting of hydrogen, lower alkyl containing one to four carbon atoms, lower alkyl containing one to four carbon atoms and substituted with a member selected from the group consisting of hydroxy, carbamyl, piperidinyl and acylamino, and together with R₃ and the nitrogen atom to which R₆ is attached form a heterocycle selected from the group consisting of dihydrooxazine and pyrrolidine; R₇ is selected from the group consisting of hydrogen, lower alkyl containing one to four carbon atoms, lower alkyl containing one to four carbon atoms and substituted with a member selected from the group consisting of hydroxy, carbamyl, piperidinyl and acylamino, and together with R₄ and the nitrogen atom to which R₇ is attached form a heterocycle selected from the group consisting of dihydrooxazine and pyrrolidine; Z represents a member selected from the group consisting of amine, acylamino and hydroxy and the salts formed by these compounds with organic or inorganic acids, in particular, their oxalates, hydrochlorides or tartrates.

The novel diphenylamines according to the invention can be obtained by two different processes.

The first process comprises reducing the corresponding indoanilines of the formula

wherein R₁ to R₇ and Z have the meaning indicated above, said reduction being performed either in an aqueous alkaline medium with a reducing agent such as sodium hydrosulfite or ammonium sulfide, or in a solvent such as an alcohol, for instance, ethanol, by catalytic hydrogenation at ambient pressure in the presence, for example, of palladium on barium sulfate on carbon.

When the process is carried out in an aqueous alkaline medium, the pH of said medium ranges generally between about 9-12, said pH having been attained generally by the inclusion therein of an alkalinizing agent such as sodium hydroxide or the like. The amount of reducing agent employed can vary but generally it will be present in amounts such that the mole ratio of indoaniline being reduced to reducing agent ranges between 1:1.5 to 1:3. This reducing reaction is generally carried out at ambient pressure and at a temperature ranging from about 25° to 50°C.

20 Alternatively, the reduction of the above indoaniline can be carried out in a solvent selected from the group consisting of ethanol and ethylacetate by catalytic hydrogenation at the ordinary pressure and a temperature of 20° to 50° in the presence of catalytic amounts of palladium on a substrate selected from the group consisting of barium sulfate and carbon. Generally, the amount of the catalyst, i.e., the palladium on said substrate, ranges between about 10 to 25 percent by weight of the indoaniline being reduced.

25 The second process, which makes it possible to obtain the diphenylamines of formula (I) wherein radicals R₆ and R₇ both designate a hydrogen atom, and Z in NH₂, comprises condensing a dinitro derivative of the formula:

30 wherein R₃, R₄ and R₅ have the meaning given above and X represents a halogen atom, on a substituted paraaminophenol of the formula:

35 wherein R₁ and R₂ have the meaning given above, thereby obtaining a dinitrodiphenylamine of the formula:

40 which is then reduced by sodium hydrosulfite in an alkaline medium or by catalytic hydrogenation in a suit-

able solvent, such as an alcohol, for instance, ethanol. In this second process the molar ratio of said dinitro derivative to said substituted paraaminophenol is generally of 1 : 1, and the condensation reaction is ordinarily carried out at the reflux temperature of the used solvent and at the ordinary pressure.

The reduction of the resulting dinitrodiphenylamine can, as stated above, be carried out in an aqueous alkaline medium having a pH ranging from about 9 to 12, the pH having been attained generally by the inclusion therein of an alkalinating agent such as sodium hydroxide or the like. This reducing reaction is generally carried out at ambient pressure and at a temperature ranging from about 30° to 60° C.

Alternatively, the reduction of the above dinitrodiphenylamine can be carried out in a solvent such as ethanol by catalytic hydrogenation at the ordinary pressure and a temperature of 20 to 50 in the presence of catalytic amounts of palladium on a substrate selected from the group consisting of barium sulfate and carbon. Generally the amount of the catalyst, i.e., the palladium on said substrate, ranges between about 10 to 25 percent by weight of the dinitrodiphenylamine being reduced.

The diphenylamines of the present invention are usefully employed to dye keratinous fibers, particularly human hair. When applied to human hair, these compounds, in an aqueous or dilute alcohol solution having a pH ranging from 4 to 11, and in extremely slight concentrations because of their good affinity for keratinous fibers and the power of the dyes obtained after oxidation either in the air or by another oxidizing agent such as hydrogen peroxide, provide an extremely rich range of shades ranging from very luminous violets to ash or silver grays passing through blues, greens, reds, pinks and golden, copper or ash blonds. The dyeings thus obtained are always characterized by their richness in glints and the pearly appearance they impart to the hair.

Thus, the present invention also relates to a dyeing composition for keratinous fibers, particularly human hair, comprising an aqueous or dilute alcohol solution of at least one compound of formula (I) of a salt of such a compound.

The dyeing compositions according to the invention can contain only the compounds of formula (I). However, they can also contain other known leuco derivatives of indoanilines, indamines or indophenols, or again oxidation dyes, such as o- or p-phenylenediamines or o- or p-aminophenols or again direct dyes.

The concentration of the compounds of formula (I) in the dyeing composition according to the present invention can vary between 0.002 and 2 percent and generally between 0.005 and 0.5 percent by weight.

The pH of the dye compositions according to the present invention can vary between 4 and 11. To regulate this pH at the desired value, there can be used as the alkalizing agent, ammonia, mono-, di- or triethanolamine, and as an acidifying agent phosphoric acid, acetic acid or lactic acid.

The dye composition according to the present invention is generally in the form of an aqueous solution, to which most often a low molecular weight alcohol, such as ethanol or isopropanol, has been added in a proportion of 20 to 70 percent by weight. Rather than a low molecular weight alcohol a glycol, such as propylene-

glycol or butylglycol, can be employed in amounts of about 1 to 6 percent by weight. The alcohol or the glycol facilitate putting the diphenylamines into solution.

Dyeing of the keratinous fibers, and particularly 5 human hair, with the dye compositions of the present invention is performed in the usual way by applying said composition to the fibers to be dyed, said composition being left in contact with the fibers for a time varying from 10 to 30 minutes. Following this application 10 the fibers can be rinsed and if desired, washed. Thereafter, the thus treated fibers are dried. If a simultaneous bleaching of the fiber is desired, there can be added to the composition, before its application, either hydrogen peroxide in amounts of 20 to 60 percent in weight of hydrogen peroxide of 20V that is to say 4 to 12 percent in weight of O₂H₂, or an equivalent quantity of another oxidizing agent of said composition.

In another embodiment of the present invention, the 20 novel diphenylamines can also be employed in the production of capillary hair-setting lotions. These lotions comprise an aqueous alcohol solution, at least one diphenylamine of Formula I or a salt thereof and at least one cosmetic resin. The amount of diphenylamine or its salt, as defined above, present in the hair-setting lotion according to this invention can be extremely slight. Such an amount generally varies between 0.002 and 1 percent by weight and preferably between 0.002 and 0.5 percent by weight of the total hair-setting lotion composition, the pH of which generally lies between 25 5-8.

Representative cosmetic resins that can be employed 30 in the hair-setting lotions of the present invention include, for instance, polyvinyl pyrrolidone having a molecular weight of 40,000-400,000, copolymer of crotonic acid and vinyl acetate, said copolymer having a molecular weight ranging from about 10,000 to 70,000, copolymer of vinyl pyrrolidone and vinyl acetate wherein the ratio of PVP to VA ranges between 40 50-70:50-30, said copolymer having a molecular weight ranging from about 30,000 to 200,000 and maleic anhydride-butylvinyl ether copolymer, a 1 percent solution of which in methylethyl ketone has a viscosity of 0.1-3.5 cps at 25°C. These resins are used in a proportion of about 1 to 3 percent by weight of the hair-setting lotion composition.

The alcohols suitable for the preparation of the hair-setting lotions according to the invention are low molecular weight alkanols, such as ethanol or isopropanol, 50 which are present in amounts of about 20 to 70 percent by weight of the hair-setting lotion composition.

The hair-setting lotions of the present invention impart to the hair a great variety of shades located in the ash blond, golden blond, ash gray or silver gray tones 55 and which tones can even be shaded violet, mauve, blue or pink. The coloring obtained are characterized by a pearly appearance and a great richness of glints and by their regularity or evenness even in the case of application to irregularly bleached hair.

60 The hair-setting lotions according to the invention are usually employed by application to wet hair, previously washed and rinsed, followed by rolling the hair up on curlers and drying the hair.

65 The following examples are intended to illustrate the present invention. Unless otherwise specified all parts and percentages are by weight and all temperatures are expressed in degrees centigrade.

EXAMPLE 1

4-hydroxy 3,5'-dimethyl 2', 4'-diamino diphenylamine is prepared according to the following reaction:

0.0086 mole (2.41 g) of sodium hydrosulfite of 75 percent purity, is dissolved in 27.5 cc of a 0.5 N soda solution. To this solution, 0.00342 mole (0.950 g) of N-[(2',4'-diamino 5'-methyl) phenyl] 3-methyl benzoquinone imine hydrochloride in suspension in 5 cc of 95° ethanol is added gradually, with stirring, keeping the temperature in the vicinity of 30°C. When the addition has been completed, the reaction mixture is allowed to become totally colorless. Then acetic acid is added to this reaction mixture until neutrality is reached, thereby precipitating the above diphenylamine which is then filtered under nitrogen, washed with water and dried under vacuum for 5 hours at 80°C. 0.60 g of pure product, which melts at 229°C, is thus obtained.

Molecular weight calculated for $C_{14}H_{17}N_3O = 243$
 Molecular weight found by potentiometric determination in acetic acid by perchloric acid = 245

Analysis	Calculated for $C_{14}H_{17}N_3O$	Found

Into 65 cc of absolute ethanol there are introduced, on the one hand, 0.025 mole (4.5 g) of 2-chloro 4-amino phenol hydrochloride, and, on the other hand, 0.025 mole (5.06 g) of 2,4-dinitro chlorobenzene and 6.2 g of molten sodium acetate. The mixture is brought to reflux, with stirring, for 6 hours then filtered while boiling to eliminate the inorganic salts.

50 cc of water are then added to the alcohol filtrate which is then cooled to 0°C. 4-hydroxy 2-methyl 2',4'-dinitro diphenylamine, which precipitates, is filtered therefrom and this product, after washing in water, recrystallization in an ethanol-water mixture and drying under vacuum, melts at 189°.

Analysis	Calculated for $C_{12}H_8N_3O_3Cl$	Found
C%	46.52	46.48
H%	2.58	2.48

Second phase — Preparation of 4-hydroxy 3-chloro 2',4'-diamino diphenylamine

0.07 mole (20 g) of sodium hydrosulfite of 75 percent purity is dissolved in 120 cc of normal soda solution. To this solution there is added gradually, with good stirring, while keeping the temperature in the vicinity of 35°C, 0.009 mole (2.79 g) of the dinitro derivative previously obtained in the first phase above. When the addition is completed and the reaction mixture colorless, it is neutralized with acetic acid thereby precipitating the above diphenylamine.

After filtering this diphenylamine from the reaction mass, washing with water and drying it under vacuum, the product melts at 203°.

Analysis	Calculated for $C_{12}H_{12}N_3OCl$	Found
C%	57.74	57.58
H%	4.84	4.87
N%	16.83	16.70

55 1 g of this diphenylamine thus obtained is then dissolved in 5 cc of a 2 N hydrochloric solution. The resulting solution is cooled to -10°. Then 15 cc of hydrochloric acid at 22°B are added. The 4-hydroxy 3-chloro 2',4'-diamino diphenylamine dihydrochloride, monohydrate crystallizes. After filtering and drying under vacuum for 3 hours, it melts with decomposition at 225°.

60 Molecular weight calculated for $C_{12}H_{12}N_3OCl \cdot 2HCl \cdot H_2O = 340.5$

Molecular weight found by potentiometric determination in water with 0.1 N soda solution = 343

EXAMPLE 3

4-hydroxy 2-methyl 2',4'-diamino diphenylamine is prepared in accordance with the following reaction:

First phase — Preparation of 4-hydroxy 2-methyl 2', 4'-dinitro diphenylamine.

Into 65 cc of absolute ethanol there are introduced, on the one hand, 0.025 mole (5.1 g) of 3-methyl 4-amino phenol hydrobromide, and, on the other hand, 0.025 mole (5.06 g) of 2,4-dinitro chlorobenzene and 6.2 g molten sodium acetate. The resulting mixture is brought to reflux and kept there with stirring for four hours, after which it is filtered while boiling to eliminate inorganic salts. 50 cc of water are then added to the alcohol filtrate which is then cooled to 0°C. 4-hydroxy 2-methyl 2', 4'-dinitro diphenylamine, which has precipitated, is then filtered therefrom. This product, after washing with water, recrystallization in an ethanol-water mixture and drying under vacuum, melts at 165°.

H%	3.83	3.87
N%	14.53	14.49

Second phase — Preparation of 4-hydroxy 2-methyl 2',4'-diamino diphenylamine

0.071 mole (20 g) of sodium hydrosulfite of 75 percent purity is dissolved in 140 cc of normal soda solution. 0.0103 mole (3 g) of the dinitro derivative obtained in the 1st phase is then gradually added to this solution with good stirring, while keeping the temperature in the vicinity of 35°C. When the addition is completed and the reaction mixture is colorless, it is neutralized with acetic acid thereby precipitating the above diphenylamine which is then filtered, washed with water and dried under vacuum five hours at 80°. 1.94 g of this pure product, which melts at 163° are thus obtained.

Analysis	Calculated for C ₁₃ H ₁₁ N ₃ O	Found

EXAMPLE 6

4-hydroxy 2,6,3',5'-tetramethyl 2',4'-diamino diphenylamine is prepared in accordance with the following reaction:

0.05 mole (14 g) of sodium hydrosulfite of 75 percent purity is dissolved in 150 cc of 1.25 N soda. To this solution there is added gradually, with good stirring, keeping the temperature in the vicinity of 40°C, 0.02 mole (5.38 g) of N-[(2',4'-diamino 3',5'-dimethyl phenyl)2,6-dimethyl benzoquinone imine in suspension in 40 cc of ethanol at 95°. The reduction reaction is rather slow. However, when the reaction mixture is colorless, it is neutralized with acetic acid thereby precipitating the above diphenylamine which is then filtered, washed with water and dried under vacuum for 5 hours at 80°. 5.01 g of this pure diphenylamine, which melts at 250°, are thus obtained.

Molecular weight calculated for $C_{16}H_{21}N_3O = 271$

Molecular weight found by potentiometric determination in acetic acid by perchloric acid = 273

Analysis	Calculated $C_{16}H_{21}N_3O$	Found

EXAMPLE 7

Second method of preparing the 4-hydroxy 2,6,3',5'-tetramethyl 2',4'-diamino diphenylamine described in Example 6:

0.027 mole (0.74 g) of N-[(2',4'-diamino 3',5'-dimethyl phenyl)2,6-dimethyl benzoquinone imine is

dissolved in 45 cc of water and 30 cc of ethyl alcohol.

To this resulting solution there are added gradually at 25°, with stirring, 3.5 cc of an ammonia solution at 16°Be previously saturated with sulfured hydrogen.

5 The completely colorless reaction mixture is then cooled at 0°, thereby precipitating the above diphenylamine which is then filtered and washed with water. There is thus obtained, after drying the said diphenylamine under vacuum at 80°, 0.65 g of the pure product which melts at 250° and which is identical with the product prepared in Example 6.

EXAMPLE 8

15 4-hydroxy 3,5,3',5'-tetramethyl 2',4'-diamino diphenylamine and its dihydrochloride are prepared as follows:

30 0.01 mole (3.05 g) of N-[(2',4'-diamino 3',5'-dimethyl phenyl)3,5-dimethyl benzoquinone imine] hydrochloride is dissolved in 90 cc of water and 60 cc of 95° ethanol. To this dilute alcohol solution there are added, drop by drop, with stirring and at 25°, 9 cc of an aqueous ammonia solution at 16°Be previously saturated with sulfured hydrogen. The reaction mixture becomes colorless. It is then cooled to 0°, and the above diphenylamine which precipitates is filtered therefrom and washed with water. After drying the same under vacuum, 2.5 g of pure product, which melts at 167°, are obtained.

Analysis	Calculated for $C_{16}H_{21}N_3O$	Found
C%	70.82	70.82
H%	7.80	7.89
N%	15.49	15.63
		70.75
		7.76
		15.47

55 0.5 g of this diphenylamine thus obtained is introduced into 10 cc of a hydrochloric solution ($d = 1.19$) at 25°. After stirring 5 minutes, the insoluble 4-hydroxy 3,3',5,5'-tetramethyl 2',4'-diamino diphenylamine dihydrochloride is filtered. This product is then first washed with hydrochloric acid $d = 1.19$, and subsequently with a little acetone. Thereafter the product is dried for three days under a nitrogen atmosphere. It melts with decomposition at 225°.

Molecular weight calculated for $C_{16}H_{21}N_3O \cdot 2HCl = 344$

Molecular weight found by potentiometric determination in water with a 0.1 N soda solution = 344

EXAMPLE 9

60 4-hydroxy 3-methyl 2',4'-diamino diphenylamine is prepared in accordance with the following reaction:

First Phase:

Preparation of 4-hydroxy 3-methyl 2',4'-dinitro diphenylamine

Into 100 cc of absolute ethyl alcohol there are introduced, on the one hand, 0.05 mole (6.15 g) of 2-methyl 4-amino phenol and, on the other hand, 0.05 mole (10.13 g) of 2,4-dinitro chlorobenzene and 6.15 g of molten sodium acetate. The resulting mixture is brought to reflux and maintained there for 5 hours with stirring, after which it is filtered while boiling to eliminate inorganic salts. After cooling the alcohol filtrate in ice, the 4-hydroxy 3-methyl 2',4'-dinitro diphenylamine, which has crystallized, is filtered therefrom. This dinitro diphenylamine after washing with water, recrystallized, in alcohol and drying under vacuum, melts at 176°.

Analysis	Calculated for C ₁₃ H ₁₁ N ₃ O ₅	Found
C%	53.98	53.86
H%	3.83	4.08
N%	14.53	14.43

Second Phase:

Preparation of 4-hydroxy 3-methyl 2',4'-diamino diphenylamine

0.0714 mole (20 g) of sodium hydrosulfite of 75 percent purity is dissolved in 225 cc of normal soda solution. To this solution there is added gradually, with good stirring, while keeping the temperature in the vicinity of 55°, 0.0138 mole (4g) of the dinitro diphenylamine obtained in the first phase. When the addition is completed and the reaction mixture is colorless, it is cooled. Then acetic acid is added to it until the pH equals 7.5, thereby precipitating the above diphenylamine which is then filtered, washed with water, and recrystallized in a dimethylformamide-water mixture. 2 g of pure product, which melts at 193°, are obtained after having been dried under vacuum for 5 hours at 80°.

Molecular weight calculated for C₁₃H₁₅N₃O = 229

Molecular weight found by potentiometric determination in acetic acid by perchloric acid = 232

Analysis	Calculated for C ₁₃ H ₁₅ N ₃ O	Found
C%	68.10	67.95
H%	6.59	6.70

EXAMPLE 11

4-hydroxy 3-methyl 2'-amino N,N-dimethylamino-4 diphenylamine is prepared in accordance with the following reaction:

50 0.025 mole (7 g) of sodium hydrosulfite of 75 percent purity is dissolved in 80 cc of a 1.25 N soda solution. To this resulting solution there is added gradually, with stirring, while keeping the temperature in the vicinity of 30°, 0.01 mole (2.91 g) of N-[(2'-amino 4-dimethylamino) phenyl] 3-methyl benzoquinoneimine hydrochloride in solution in 30 cc of water. When the addition is completed, the reaction mixture is allowed to become totally colorless. The acetic acid is added to pH 7 to precipitate the above diphenylamine which is then filtered under nitrogen, washed with water and dried under vacuum for 5 hours at 80°. 2.35 g of the pure diphenylamine which melts at 187° are thus obtained.

EXAMPLE 24

Third method for preparing 4-hydroxy 2,6,3',5'-tetramethyl 2', 4'-diamino diphenylamine already described in Examples 6 and 7 is as follows:

0.00372 mole (1 g) of N -[(2', 4'-diamino 3', 5'-dimethyl phenyl) 2,6-dimethyl benzoquinoneimine is dissolved in 100 cc of absolute ethyl alcohol. Then palladium or barium sulfate (5 percent Pd/SO_4 , Ba Englehard Industries) is added as the catalyst and the product is reduced in the usual way by hydrogen at ambient pressure. After 15 minutes, the alcohol solution has become completely colorless. This solution is then filtered to recover the catalyst and it is concentrated under vacuum and nitrogen up to 15 cc. 40 cc of water are then added and the above diphenylamine which is filtered and dried under vacuum exhibits a melting point of 251° and does not give a lowering of the melting point when used in mixture with the products prepared according to the processes described in Examples 6 and 7.

EXAMPLE 25

4-hydroxy 3,6,5'-trimethyl 2', 4'-diamino diphenylamine is prepared as follows:

First phase — Preparation of 4-hydroxy 3,6,5'-trimethyl 2', 4'-dinitro diphenylamine

Into 300 cc of absolute ethanol there are introduced, on the one hand, 0.04 mole (10.44 g) of 2,4-dinitro 5-bromo toluene, and, on the other hand, 0.04 mole (5.48 g) of 2,5-dimethyl 4-amino phenol and 4.1 g of molten sodium acetate. The resulting mixture is heated to reflux for 5 hours with stirring and filtered hot to eliminate the inorganic salts. 300 cc of water are then added and the mixture cooled to 0° thereby precipitating 11 g of 4-hydroxy 3,6,5'-trimethyl 2', 4'-dinitro diphenylamine which are filtered and which, after recrystallization in ethanol, melt at 174°.

100 g

This hair dye composition when applied for 20 minutes to 95 percent naturally white hair, imparts thereto, after rinsing and shampooing, a pearly glycine shade.

45

EXAMPLE 41

The following hair dye composition is prepared:

50

Dye of Example 13
Ethyl alcohol, 96° titer
Water, q.s.p.
1% lactic acid solution, q.s.p. pH 7

0.15 g
50 g
100 g

55

This hair dye composition when applied for 20 minutes to 95 percent naturally white hair, imparts thereto, after rinsing and shampooing, an iridescent violet pink shade.

60

EXAMPLE 42

The following hair dye composition is prepared:

65 Dye of Example 16
Ethyl alcohol, 96° titer
Water, q.s.p.
1% lactic acid solution, q.s.p. pH 6

0.03 g
30 g
100 g

This hair dye composition when applied for 30 minutes to bleached hair, imparts thereto, after rinsing and shampooing, a cyclamen coloring.

EXAMPLE 43

The following hair dye composition is prepared:

Dye of Example 1	0.005 g
Ethyl alcohol, 96° titer	20 g
Water, q.s.p.	100 g
1% lactic acid solution, q.s.p. pH 6.5	

This hair dye composition when applied for 20 minutes to bleached hair, imparts thereto, after rinsing and shampooing, a bright pink shade with golden glints.

EXAMPLE 44

The following hair dye composition is prepared:

Dye of Example 12	0.04 g
Ethyl alcohol, 96° titer	30 g
Water, q.s.p.	100 g
1% lactic acid solution, q.s.p. pH 7.5	

This hair dye composition when applied for 25 minutes to 95 percent naturally white hair, imparts thereto, after rinsing and shampooing, a pearly rose shade.

EXAMPLE 45

The following hair dye composition is prepared:

Dye of Example 17	0.1 g
Butylglycol	5 g
Lauryl alcohol oxyethylenated with 10.5 moles of ethylene oxide	5 g
Water, q.s.p.	100 g
Ammonia at 22° Be., q.s.p. pH 9	

This hair dye composition when applied for 20 minutes to bleached hair, imparts thereto, after rinsing and shampooing, a golden blond shade with pink glints.

EXAMPLE 46

The following hair dye composition is prepared:

Dye of Example 21	0.075 g
Ethyl alcohol, 96° titer	30 g
Water, q.s.p.	100 g
1% lactic acid solution, q.s.p. pH 6	

This hair dye composition when applied for 20 minutes to bleached hair, imparts thereto, after rinsing and shampooing, a turquoise blue shade.

EXAMPLE 47

The following hair dye composition is prepared:

Dye of Example 22	0.09 g
Ethyl alcohol, 96° titer	30 g
Water, q.s.p.	100 g

This hair dye composition when applied for 20 minutes to bleached hair, imparts thereto, after rinsing and shampooing, a pale blue green shade with golden glints.

EXAMPLE 48

The following hair dye composition is prepared:

Dye of Example 19	0.1 g
4-hydroxy 2',4'-diamino 5'-methoxy diphenylamine dihydrochloride monohydrate	0.02 g
Ethyl alcohol, 96° titer	20 g
Water, q.s.p.	100 g
Ammonia at 22° Be., q.s.p. pH 9	

This hair dye composition when applied for 20 minutes to natural medium brown hair, imparts thereto, after rinsing and shampooing, a dark brown coloring with violine glints.

EXAMPLE 49

The following hair-setting lotion composition is prepared:

Dye of Example 17	0.05 g
Vinyl acetate-crotonic acid copolymer (90% vinyl acetate, 10% crotonic acid, molecular weight 45,000 to 50,000)	2 g
Ethyl alcohol, 96° titer	50 g
Water, q.s.p.	100 g
Ammonia at 22° Be., q.s.p. pH 6.5	

This hair-setting lotion when applied to bleached hair imparts thereto a golden blond shade with pink glints.

EXAMPLE 50

The following hair-setting lotion composition is prepared:

Dye of Example 23	0.18 g
4-hydroxy 2,4'-diamino 5-methyl diphenylamine dihydrochloride	0.05 g
Vinyl acetate-crotonic acid copolymer (90% vinyl acetate, 10% crotonic acid - molecular weight 45,000 to 50,000)	2 g
Ethyl alcohol, 96° titer	50 g
Water, q.s.p.	100 g
Ammonia at 22° Be., q.s.p. pH 8.5	

40 This hair-setting lotion when applied to bleached hair, imparts thereto a light golden bronze shade.

EXAMPLE 51

The following hair-setting lotion composition is prepared:

Dye of Example 10	0.005 g
Vinyl acetate-crotonic acid copolymer (90% vinyl acetate, 10% crotonic acid, molecular weight 45,000 to 50,000)	2 g
Isopropyl alcohol, 96° titer	50 g
Water, q.s.p.	100 g
Ammonia at 22° Be., q.s.p. pH 8	

55 This hair-setting lotion when applied to bleached hair, imparts thereto a pearly blond shade with pink glints.

EXAMPLE 52

The following hair-setting lotion composition is prepared:

Dye of Example 19	0.055 g
Vinyl acetate-crotonic acid copolymer (90% vinyl acetate, 10% crotonic acid, molecular weight 45,000 to 50,000)	2 g
Ethyl alcohol, 96° titer	50 g
Water, q.s.p.	100 g
Ammonia at 22° Be., q.s.p. pH 7	

This hair-setting lotion when applied to 95 percent naturally white hair, imparts thereto, a silvery gray shade with light mauve glints.

EXAMPLE 53

The following hair-setting lotion composition is prepared:

Dye of Example 9	0.065 g
Vinyl acetate-crotonic acid copolymer (90% vinyl acetate, 10% crotonic acid, molecular weight 45,000 to 50,000)	2 g
Ethyl alcohol, 96° titer	50 g
Water, q.s.p.	100 g
Ammonia at 22° Be., q.s.p. pH 8.5	

This hair setting lotion when applied to bleached hair, imparts thereto a pearly ash blond shade.

EXAMPLE 54

The following hair-setting lotion composition is prepared:

Dye of Example 4	0.1 g
Vinyl acetate-crotonic acid copolymer (90% vinyl acetate, 10% crotonic acid, molecular weight 45,000 to 50,000)	1 g
Ethyl alcohol, 96° titer	25 g
Water, q.s.p.	100 g
Ammonia at 22° Be., q.s.p. pH 8.5	

This hair-setting lotion when applied to bleached hair, imparts thereto a pearly pink shade.

EXAMPLE 55

The following hair-setting lotion composition is prepared:

Dye of Example 10	0.5 g
Vinyl acetate-crotonic acid copolymer (90% vinyl acetate, 10% crotonic acid, molecular weight 45,000 to 50,000)	2 g
Ethyl alcohol, 96° titer	50 g
Water, q.s.p.	100 g
Triethanolamine, q.s.p. pH 7.5	

This hair-setting lotion composition when applied to bleached hair, imparts thereto a very intense mauve shade.

EXAMPLE 56

The following hair-setting lotion composition is prepared:

Dye of Example 13	0.08 g
Vinyl acetate-crotonic acid copolymer (90% vinyl acetate, 10% crotonic acid, average molecular weight 45,000 to 50,000)	2 g
Ethyl alcohol, 96° titer	50 g
Water, q.s.p.	100 g
Ammonia at 22° Be., q.s.p. pH 6	

This hair-setting lotion when applied to bleached hair imparts thereto a pale pink shade with golden glints.

EXAMPLE 57

The following hair-setting lotion composition is prepared:

Dye of Example 23	0.08 g

-Continued

5	Vinyl acetate-crotonic acid copolymer (90% vinyl acetate, 10% crotonic acid, average molecular weight 45,000 to 50,000)	2 g
	Ethyl alcohol, 96° titer	50 g
	Water, q.s.p.	100 g

This hair-setting lotion when applied to bleached hair imparts thereto a pale golden green shade.

EXAMPLE 58

The following hair-setting lotion composition is prepared:

10	Dye of Example 2	0.11 g
	Vinyl acetate-crotonic acid copolymer (90% vinyl acetate, 10% crotonic acid, molecular weight 45,000 to 50,000)	2 g
	Ethyl alcohol, 96° titer	50 g
	Water, q.s.p.	100 g

This hair-setting lotion when applied to bleached hair imparts thereto a silvery beige gray shade.

EXAMPLE 59

The following hair-setting lotion composition is prepared:

15	Dye of Example 5	0.1 g
	Vinyl acetate-crotonic acid copolymer (50% vinyl acetate, 10% crotonic acid, molecular weight 45,000 to 50,000)	2 g
	Ethyl alcohol, 96° titer	50 g
	Water, q.s.p.	100 g

This hair-setting lotion when applied to bleached hair imparts thereto a pearly pink blond shade.

EXAMPLE 60

The following hair-setting lotion composition is prepared:

20	Dye of Example 21	0.05 g
	Vinyl acetate-crotonic acid copolymer (90% vinyl acetate, 10% crotonic acid, molecular weight 45,000 to 50,000)	2 g
	Isopropyl alcohol, 96° titer	50 g
	Water, q.s.p.	100 g

This hair-setting lotion when applied to bleached hair imparts thereto a light pearly turquoise blue shade.

EXAMPLE 61

The following hair-setting lotion composition is prepared:

25	Dye of Example 15	0.055 g
	Vinyl acetate-crotonic acid copolymer (90% vinyl acetate, 10% crotonic acid, molecular weight 45,000 to 50,000)	1.5 g
	Ethyl alcohol, 96° titer	35 g
	Water, q.s.p.	100 g

This hair-setting lotion when applied to bleached hair imparts thereto a pearly rose mauve shade.

EXAMPLE 62

The following hair-setting lotion composition is prepared:

Dye of Example 4	0.005 g
Vinyl acetate-crotonic acid copolymer (vinyl acetate 90%, crotonic acid 10%, molecular weight 45,000 to 50,000)	2 g
Ethyl alcohol, 96° titer	50 g
Water, q.s.p.	100 g
Ammonia at 22°Be., q.s.p. pH 8.5	

This hair-setting lotion when applied to bleached hair imparts thereto a golden blond shade with pink glints.

EXAMPLE 63

The following hair dye composition is prepared:

Dye of Example 20	0.15 g
Ethyl alcohol, 96° titer	30 g
Water, q.s.p.	100 g
Ammonia at 22°Be., q.s.p. pH 9	

This hair dye composition when applied for 20 minutes to bleached hair imparts thereto, after rinsing and shampooing, a light turquoise blue shade.

EXAMPLE 64

The following hair-setting lotion composition is prepared:

Dye of Example 14	0.045 g
Vinyl acetate-crotonic acid copolymer (90% vinyl acetate, 10% crotonic acid, molecular weight 45,000 to 50,000)	2 g
Ethyl alcohol, 96° titer	50 g
Water, q.s.p.	100 g
Ammonia at 22°Be., q.s.p. pH 7	

This hair-setting lotion when applied to bleached hair imparts thereto a pale green shade.

EXAMPLE 65

The following hair dye composition is prepared:

Dye of Example 18	0.105 g
Ethyl alcohol, 96° titer	20 g
Water, q.s.p.	100 g
Ammonia at 22°Be., q.s.p. pH 9	

This hair dye composition when applied for 20 minutes to 95 percent naturally white hair, imparts thereto, after rinsing and shampooing, a rose beige shade.

EXAMPLE 66

The following hair dye composition is prepared:

Dye of Example 18	0.1 g
2,6-diamino 4,N,N-diethylamino-2 phenol trihydrochloride	0.03 g
Ethyl alcohol, 96° titer	20 g
Water, q.s.p.	100 g
Ammonia at 22°Be., q.s.p. pH 9	

This hair dye composition when applied for 20 minutes to 95 percent naturally white hair, imparts thereto, after rinsing and shampooing, a dark copper blonde shade.

EXAMPLE 67

The following hair dye composition is prepared:

5	Dye of Example 8	0.1 g
2	2-amino 4-methoxy phenol hydrochloride	0.02 g
4,4'-dihydroxy 3,5-dimethyl diphenylamine	0.06 g	
Ethyl alcohol, 96° titer	20 g	
Water, q.s.p.	100 g	
10	Ammonia at 22°Be., q.s.p. pH 9	

This hair dye composition when applied for 20 minutes to 95 percent naturally white hair, imparts thereto, after rinsing and shampooing, a slightly mauve silvery gray shade.

EXAMPLE 68

The following hair dye composition is prepared:

20	Dye of Example 2	0.12 g
2	Ethyl alcohol, 96° titer	30 g
20	20 volume hydrogen peroxide	50 g
Water, q.s.p.	100 g	
15	Ammonia at 22°Be., q.s.p. pH 9	

This hair dye composition when applied for 20 minutes to 95 percent naturally white hair, imparts thereto, after rinsing and shampooing, a silvery blue gray shade.

EXAMPLE 69

The following hair dye composition is prepared:

35	Dye of Example 25	0.055 g
2	Ethyl alcohol, 96° titer	20 g
20	Water, q.s.p.	100 g
15	Ammonia at 22°Be., q.s.p. pH 10	

This hair dye composition when applied for 20 minutes to 95 percent naturally white hair, imparts thereto, after rinsing and shampooing, a silvery glycine shade.

EXAMPLE 70

The following hair dye composition is prepared:

45	Dye of Example 26	0.08 g
2	Ethyl alcohol, 96° titer	30 g
20	Water, q.s.p.	100 g
50	The pH of this composition is 8	

This hair dye composition when applied for 20 minutes to bleached hair, imparts thereto, after rinsing and shampooing, an intense cyclamen shade.

EXAMPLE 71

The following hair dye composition is prepared:

60	Dye of Example 8	0.035 g
2	Nitroorthophenylenediamine	0.08
4	Ethyl alcohol, 96° titer	20 g
20	Water, q.s.p.	100 g
15	Ammonia at 22°Be., q.s.p. pH 9.5	

This hair dye composition when applied for 20 minutes to 95 percent naturally white hair, imparts thereto, after rinsing and shampooing, a very luminous bronze green shade.

EXAMPLE 72

The following hair dye composition is prepared:

Dye of Example 10	0.025 g
N-[(2',4'-diamino 5'-methyl) phenyl] benzoquinoneimine	0.075 g
Nitrometaphenylenediamine	0.04 g
Ethyl alcohol, 96° titer	20 g
Water, q.s.p.	100 g
Ammonia at 22°Be., q.s.p. pH 9.5	

This hair dye composition when applied for 20 minutes to 95 percent naturally white hair, imparts thereto, after rinsing and shampooing, a chestnut with golden glints.

What is claimed is:

1. A composition for dyeing keratinous fibers comprising a solution in a solvent selected from the group consisting of water and an aqueous alcohol solution of a diphenylamine selected from the group consisting of

a. a diphenylamine of the formula

wherein R₁ and R₂ each independently represent a member selected from the group consisting of hydrogen, halogen and lower alkyl with the proviso that at least one of R₁ and R₂ is other than hydrogen; R₃, R₄ and R₅ each independently are selected from the group consisting of hydrogen, lower alkyl containing one to four carbon atoms, hydroxy lower alkyl containing one to four carbon atoms and methoxy R₆ is selected from the group consisting of hydrogen, lower alkyl containing one to four carbon atoms and hydroxy lower alkyl containing one to four carbon atoms; R₇ is selected from the group consisting of hydrogen, lower alkyl containing one to four carbon atoms and hydroxy lower alkyl containing one to four carbon atoms; and Z is selected from the group consisting of amino, acylamino and hydroxy; and

b. the acid salts of said diphenylamine of (a).

2. The composition of claim 1 wherein said diphenylamine is 4-hydroxy-3,5,3',5'-tetramethyl-2',4'-diamino diphenylamine.

3. The composition of claim 1 wherein said diphenylamine is present in amounts of 0.002-2 percent by weight of said composition.

4. The composition of claim 1 having a pH between 5 and 11.

5. The composition of claim 1 which also includes a dye selected from the group consisting of ortho- and para-phenylenediamines, ortho- and paraaminophenols, other leuco derivatives of indoanilines, indamines or indophenols, and direct dyes.

6. The composition of claim 1 wherein said alcohol is a glycol in amounts of 1 to 6 percent by weight.

7. The composition of claim 6 wherein said glycol is selected from the group consisting of propylene glycol and butylglycol.

8. The composition of claim 1 wherein said alcohol is a low molecular weight alcohol in amounts of 20 to 70 percent by weight.

9. The composition of claim 8 wherein said low molecular weight alcohol is selected from the group consisting of ethanol and isopropanol.

10. The composition of claim 1 wherein said solvent is an aqueous alcohol solution and which also includes a cosmetic resin.

11. The composition of claim 10 wherein said cosmetic resin is selected from the group consisting of polyvinylpyrrolidone, copolymer of crotonic acid-vinyl acetate, copolymer of vinylpyrrolidone and vinyl acetate and copolymer of maleic anhydride and butylvinyl ether.

12. The composition of claim 10 wherein said cosmetic resin is present in amounts of 1 to 3 percent by weight.

13. A process of dyeing keratinous fibers comprising impregnating said fibers with the composition of claim 1, permitting said composition to remain in contact with said fibers for a time ranging from about 10 to 30 minutes, rinsing said fibers and drying said fibers.

14. A process for treating human hair comprising applying to hair previously washed and rinsed, a composition defined in claim 10, rolling said hair up on curlers and drying said hair.

15. The process of claim 13, comprising adding to the composition before its application, either hydrogen peroxide in an amount of 4 to 12 percent in weight or an equivalent quantity of another oxidizing agent, of said composition.

UNITED STATES PATENT OFFICE
CERTIFICATE OF CORRECTION

Patent No. 3,787,174

Dated January 22, 1974

Inventor(s) Gregoire Kalopissis; Andree Bugaut
and Francoise Estradier

It is certified that error appears in the above-identified patent
and that said Letters Patent are hereby corrected as shown below:

Under the heading "Foreign Application Priority Data", add
--Luxembourg 63,527, July 14, 1971--.

Signed and sealed this 16th day of July 1974.
